HERMANN LEMP AND MERLE J. WIGHTMAN, OF HARTFORD, CONNECTICUT,
ASSIGNORS TO THE SCHUYLER ELECTRIC LIGHT COMPANY.

THERMOSTATIC CUT-OUT FOR INCANDESCENT LAMPS.

SPECIFICATION forming part of Letters Patent No. 352,622, dated November 16, 1886.

Application filed August 27, 1886. Serial No. 211,992. (No model.)

To all whom it may concern:

Be it known that we, HERMANN LEMP and MERLE J. WIGHTMAN, citizens of the United States, and residents of Hartford, in the county 5 of Hartford and State of Connecticut, have invented certain new and useful Thermostatic Cut-Outs for Incandescent Electric Lamps, of which the following is a specification.

Our invention relates to the construction of incandescent lamps, and involves more particularly features of improvement in the arrangement of conductors within the lamp, whereby the lamp is especially adapted for use on circuits carrying heavy currents.

15 The object of our invention is more particularly to so construct the lamp that in case of the rupture of the filament of the same a new path for the electric current may be automatically formed so as to short-circuit or cut out 20 the lamp from the system.

In an application filed of even date herewith we have described several ways of automatically short-circuiting or cutting out an incandescent lamp from the system upon the 25 rupture of the filament, by utilizing the increased temperature developed within the lamp upon the formation of the electric arc to release movable metallic contacts normally held out of operative position, and which are 30 thereupon brought together to form a new path for the current.

Our present invention involves another application of principle of thermostatic action within the lamp to accomplish the same result, 35 and is based, primarily, upon the unequal expansion of different kinds of metal under the influence of heat.

To this end our invention consists of thermostatic expansion-pieces located within the 40 lamp and in proximity to the filament, and adapted to establish an electrical connection between the leading-in conductors upon an increase of temperature due to the rupture of the filament.

45 In the accompanying drawings, Figure 1 represents a side elevation of a part of a lamp embodying our invention. Fig. 2 is a horizontal section through the line X X of Fig. 1. Fig. 3 is a section through the same line showing the relative position of the conductors after the rupture of the filament by the electric

arc. Fig. 4 is a detail view of the leading-in conductor. Fig. 5 is an end elevation of the leading-in conductors with the copper strips attached.

55 In carrying out our invention in the manner herein illustrated the leading-in conductors C C of the lamp A are constructed of platinum, and are preferably formed in the shape of flat rectangular strips, as shown. These 60 conductors enter the lamp in different vertical planes, as indicated in Figs. 2, 3, and 5.

At some point within the lamp and near the filament the conductors are brought into immediate proximity by means of horizontal extensions c c' of the same material extending, respectively, over the face of the opposite conductors, and in proximity thereto, but out of contact therewith under the normal conditions of the lamp.

70 To the outer side of these extensions are bolted or riveted the expansion-pieces D D' of corresponding size and shape and oppositely attached to the extensions—that is to say, the strip D being bolted or riveted to the extension c, and the strip D' being bolted or riveted to the extension c', as shown in Figs. 2 and 3, so that the leading-in conductors with their extensions and the copper strips form at this point two parallel plates. The expansion-pieces D D' are composed of some metal which 75 expands unequally under the influence of heat as compared with the part of the lamp to which they are attached. As the expansion-pieces are shown in the present case as attached directly to the platinum conductors, they are 80 made of some metal which expands more than the platinum conductors under the influence of heat, preferably copper.

85 The operation of the device is as follows: 90 When from any cause the filament of the lamp is ruptured, an electric arc is thereby formed between its broken ends, and there is at once developed a sensible increase of heat within the lamp, due to the increased resistance of 95 the electric arc. The copper strips and the platinum conductors and extensions being equally subjected to the influence of the heat, the copper strips, which expand considerably more than the corresponding platinum surfaces to which they are rigidly attached, tend 100 to warp the combined mass and force the two

platinum surfaces together on each side of the lamp—that is to say, the extension *c* being turned in and forced toward the leading-in conductor *C* in its immediate proximity, and 5 the extension *c'* being turned in and forced toward the neighboring leading-in conductor *C*, as indicated by the arrows in Fig. 2 and shown in Fig. 3, thereby forming a new path for the electric current across the lamp at that point. 10 As the ends of the expansion-pieces which are extended over the body of the leading-in conductors are not rigidly attached thereto, it is clear that those ends of the expansion-pieces are permitted to expand freely under the influence of heat, and will have no tendency, or 15 very little tendency, to move the conductors themselves, but the movement will be as indicated in Fig. 3.

In this application we have described a lamp 20 which involves the use of two expansion-pieces attached, respectively, to the two conductors; but it is evident that the same result could be accomplished by the use of a single expansion-piece which would produce the whole of the 25 movement necessary to establish the new path for the current. We have also shown these expansion-pieces as attached directly to the leading-in conductors; but it is evident that these pieces might be applied to other devices 30 or parts having connection with such conductors, the sole purpose of the invention in this respect being to avail ourselves of the unequal expansion of the different metals in order to establish an electrical connection between the 35 leading-in conductors upon the increase of heat due to the rupture of the filament.

What we claim as our invention is—

1. The combination, with an incandescent

lamp, of thermostatic expansion-pieces located within the lamp and in proximity to the filament, and adapted to close a circuit through the conductors upon an increase of temperature due to the rupture of the filament, as and for the purpose described. 40

2. The combination, with an incandescent 45 lamp, of thermostatic expansion-pieces attached to the conductors within the lamp and in proximity to the filament, and adapted to force the same into electrical connection upon an increase of temperature due to the rupture 50 of the filament, as and for the purpose described.

3. The combination, with an incandescent lamp, of leading-in conductors brought into proximity at some point within the lamp, thermostatic expansion-pieces attached to such conductors at that point and adapted to force them into contact upon an increase of temperature due to the rupture of the filament, as 55 and for the purpose described. 60

4. The combination, with an incandescent lamp, of a thermostatic expansion-piece attached to a leading-in conductor of different material therefrom, whereby such conductor is forced into electrical connection with the 65 other conductor upon an increase of temperature due to the rupture of the filament, as and for the purpose described.

Signed at Hartford, in the county of Hartford and State of Connecticut, this 13th day of 70 August, A. D. 1886.

HERMANN LEMP.
MERLE J. WIGHTMAN.
